To all whom it may concern:

Be it known that I, JOHN D. HUSSEY, of Maben, in the county of Webster and State of Mississippi, have invented a certain new 5 Design for Grave Covers; and I do hereby declare the following to be a full, clear, and exact description of the invention, such as will enable others skilled in the art to which it pertains to make and use it, reference being had to the accompanying drawings, which form part of this specification.

My invention has relation to designs for grave covers, of which the following is the specification, reference being had to the accompanying drawings forming a part thereof.

Figure 1 is a perspective view of a grave cover which embodies my design. Fig. 2 is a longitudinal vertical section of the same.

My design consists of a rectangular base A 20 having thereon a raised portion B, which tapers at the sides from the point c to its opposite end. Placed at one end of the said raised

At 25 the opposite end of the raised portion is a vertical portion or slab D of the same width as the end of the raised portion, and its upper end is made flat with rounded corners.

The raised portion B tapering as described 30 is the same shape in plan as a coffin as clearly shown.

Having thus described my invention, what I claim, and desire to secure by Letters Patent, is—

The design for a grave cover substantially as herein shown and described.

In testimony whereof I affix my signature in presence of two witnesses.

JOHN D. HUSSEY.
